UNITED STATES PATENT OFFICE.

GEORGE H. BRADFORD, OF BERKELEY, CALIFORNIA.

GYRATORY ORE-MILL.

1,036,433.

Specification of Letters Patent. Patented Aug. 20, 1912.

Application filed October 4, 1911. Serial No. 652,694.

To all whom it may concern:

Be it known that I, GEORGE H. BRADFORD, a citizen of the United States, residing at Berkeley, in the county of Alameda and State of California, have invented new and useful Improvements in Gyratory Ore-Mills, of which the following is a specification.

The present invention relates to improvements in gyratory ore mills, the object of 10 the invention being to provide an apparatus of this character, for recovering gold and other precious metals, from which the amalgam can be removed with greater ease and rapidity than heretofore, and which will be 15 efficient in operation and durable in use.

In the accompanying drawing, the figure is a vertical section of the mill.

Referring to the drawing, 1 indicates the mortar or base, having a wall 2 formed at 20 the top with a flange 3, to which is secured a cylindrical casing 4. The wall 2 of said base and said casing 4 are formed at suitable vertical intervals with apertures 5, 6, and 7, so that by suitably closing said apertures, 25 by means of shutters 8, the degree of fineness to which the ore is to be pulverized may be regulated as desired. Thus, if the lowermost aperture 5 is opened, so that the level of the water in the mill stands only at said 30 aperture, the material will be pulverized to about 40 mesh. If the lowermost aperture 5 be closed, and the next aperture 6 opened, the material will be pulverized to about 80 mesh. If the aperture 6 is closed, and the 35 uppermost aperture 7 opened, then the material will be pulverized to about 150 mesh. And if this aperture be closed, so that the water can escape only over the top of the wall 4, then the material will be pulverized 40 still finer.

Supported upon the base 1 centrally within the wall thereof is a circular die 9 formed near its margin with a circular trough 10, its central part 11 rising in a conical shape 45 to form a distributing head, and having cast therein a staple 12 for convenience in handling the same. Between said die and the wall of the mortar or base is a ring 13, having formed in the top thereof a trough 14 50 for containing mercury. The mercury can be drawn from said trough by a vertical aperture 15 through said ring and base and closed by a screw plug 16. Supported on vertical posts 17 are bearings 18 for a counter shaft 19, which carries pulleys 20, by 55 which said shaft can be driven from any

suitable source of power. Said shaft 19 has secured thereon a bevel pinion 21 meshing with a bevel gear 22 on a vertical shaft 23 mounted in bearings 24, secured to transverse beams 25, the lower end of which shaft 23 carries a gyrating arm 26 upon which is secured a socketed part 27 in which is a ball 28 mounted upon a gyrating shaft 29. Upon said shaft is carried a feed disk 30, and to the lower end of said shaft is secured, as shown at 31, a boss head 32, which is secured, as shown at 33, both to a feed hopper 34 and to a muller 35. The material fed into said hopper flows through 70 the central conduit 36 formed in the muller and on to the distributing head 11. Secured to said muller is an annular shoe 37. It is in the construction of this shoe and of the parts immediately connected therewith that 75 my invention principally resides. Heretofore, owing to the location of the mercury trough relative to the other parts of the apparatus, great difficulty and inconvenience have been experienced in removing from the 80 mortar the amalgam containing the precious metal. Moreover, with such prior forms of gyratory mills, should the motion of the mill unduly slacken or cease, the mill is liable to become clogged up with sand, which 85 could not, in such a case, be removed except by raising the muller out of the mortar, a laborious and tedious operation. In my improvement, the mercury trough 14 is 90 placed on the outside of the shoe, so that it 95 is easily accessible. Furthermore, to prevent the sand clogging up the mill, the shoe is formed with an outwardly extending flange 38, which, in the gyratory motion of the mill, tends to continually deflect or depress 95 the pulverized material on to the mercury in the trough, while at the same time the said motion produces a continuous circular 100 or rotary wave which, continually traveling around the mill, washes the light from the heavy particles. The light particles pass upward with the water continually supplied to the mill, while the heavy numerals are forced into the trough of mercury.

A further improvement consists in the 105 means for securing the annular shoe of the muller, which comprises long bolts 39 which pass through the flange 38 of the shoe, the head 40 of each bolt resting against said flange, while the upper end of the bolt passes 110 out through a flange 41 of the boss head, and is secured thereto by means of a nut 42.

Heretofore, the shoe has been secured to the muller by means of bolts located wholly within the mortar itself, and therefore under water, and not open to observation or easy 5 of access. Consequently, it has not infrequently happened that a bolt or nut has become loose, and dropping between the shoe and die, has become ground up in the mill. By extending the ends of the bolts up to the 10 flange of the boss head, said ends are always under observation, so that such damage cannot occur. Furthermore, the upper end of each bolt is surrounded by a powerful coiled spring 43, which is contained in a recess 44 15 formed in the muller and boss head, and pressed at its lower end against an upwardly facing shoulder 45 formed on said muller and at its upper end against the nut 42 on said bolt. These springs hold the shoe 20 against the muller tightly at all times so that the shoe does not by the unscrewing of the nuts 42 become loose from the muller. Moreover said springs afford sufficient resiliency to absorb the jar and shock taking place 25 in the mill and prevent crystallization.

An important feature of my invention resides in the forms of the meeting surfaces of the shoe and die. I make both the inner upper surface 50 and the outer upper surface 30 face 51 of the die 9, and the inner lower surface 52 and the outer lower surface 53 of the shoe 37 exactly conical, the angle which the generatrix makes with the horizontal plane being 30° for the surfaces 50, 52, and $22\frac{1}{2}^{\circ}$ 35 for the surfaces 51, 53. I find that a gyroscopic mill having a shoe and die thus formed possesses great efficiency.

The operation of the apparatus will be

readily understood from the foregoing description.

The ore to be pulverized is fed with water through an automatic feeder (not shown) controlled by the feed disk, into the hopper and through the central conduit 36 on to the distributing head, whence it passes between the shoe, and die, and is pulverized thereby. The oblique flange 38 on the outside of the shoe tends to throw the material downward, the heavy particles being thrown against the mercury in the mercury trough, while the lighter particles escape upward with the water through one of the outlet apertures 5, 6, 7 or over the edge of the upper casing. At suitable intervals, the amalgam containing the precious metal is drawn off.

I claim:—

A mill comprising an annular die, a muller, means for imparting a gyratory motion to said muller, an annular shoe, and means for securing said shoe to said muller consisting of bolts connected at the lower ends to said shoe, parts carried by the upper ends of said bolts, the muller having upwardly facing shoulders adjacent to which said bolts pass, and coiled springs around said bolts 60 pressing at one end against said shoulders, and at the other end against said parts on the bolts.

In testimony whereof I have hereunto set my hand in the presence of two subscribing 70 witnesses.

GEORGE H. BRADFORD.
